UNITED STATES PATENT OFFICE.

FREDERICK S. CHASE, OF WATERBURY, CONNECTICUT, ASSIGNOR TO THE WATERBURY MANUFACTURING COMPANY, OF SAME PLACE.

DESIGN FOR AN OIL-CAN.

SPECIFICATION forming part of Design No. 24,069, dated February 26, 1895.

Application filed January 14, 1895. Serial No. 534,919. Term of patent 7 years.

To all whom it may concern:

Be it known that I, FREDERICK S. CHASE, of Waterbury, in the county of New Haven and State of Connecticut, have invented a new Design for Oil-Cans; and I do hereby declare the following, when taken in connection with the accompanying drawings and the letters of reference marked thereon, to be a full, clear, and exact description of the same, and which said drawings constitute part of this specification.

This invention relates to a design for oil-cans, and the design consists in the configuration and ornamentation as shown in the accompanying illustrations, wherein—

Figure 1 shows an elevation and Fig. 2, a section on line X—X of Fig. 1.

As herein shown, my newly designed oil-can has a cylindrical body A, furnished at its lower end with two circumferential, out-

wardly projecting beads a' , and at its upper end with a corresponding bead a^2 , and also with a wider knurled bead a^3 , from which point the body has a tapering shoulder A', which merges into a neck a^4 . Above the neck a^4 is seen the knurled overhanging flange B of the spout, over which is fitted the long cylindrical cap C, all as shown in the accompanying illustrations.

I claim—

The design for an oil-can as herein shown and described.

In testimony whereof I have signed this specification in the presence of two subscribing witnesses.

FREDERICK S. CHASE.
